UNITED STATES PATENT OFFICE.

MAX A. SKALL, OF NEW YORK, N. Y.

TICKET-RACK AND STORAGE SYSTEM FOR SAME.

1,141,274.

Specification of Letters Patent. Patented June 1, 1915.

Application filed December 18, 1913. Serial No. 807,394.

To all whom it may concern:

Be it known that I, MAX A. SKALL, a citizen of the United States, and residing at New York city, in the county and State of New York, have invented certain new and useful Improvements in Ticket-Racks and Storage Systems for Same, of which the following is a specification.

The present invention relates to improvements in devices for storing theater or other tickets or similar articles, so that one of each kind of the tickets is at all times easily obtainable, while the rest of them are safely stored in receptacles, but ready for immediate use.

Another object of my invention is to store many kinds of tickets in a systematic manner using a minimum of space.

With the above and other objects in view, the present invention also consists of certain novel details of construction and arrangement of parts hereinafter described and particularly set forth in the appended claims.

Reference is to be had to the accompanying drawings, forming a part of this specification, in which similar characters of reference indicate corresponding parts in all the figures, and in which—

Fig. I is an isometric view of a revolving stand for ticket racks, of which parts are broken away for better illustration. Fig. II shows a section through a hinge bar and pin in upper plate 6. Fig. III shows a single ticket holder in isometric view. Fig. IV illustrates the mode of assembling the ticket holders into a ticket rack, the upper left hand corner of a ticket rack; without frame, is shown in isometric view. Fig. V is a section on the line A—A indicated in Fig. I. Fig. VI is an isometric view of the storage cabinet for tickets. Fig. VII is a plan view of the hinge connection of a ticket rack to the ticket storage cabinet. Fig. VIII is a section on line B.—B. of Fig. VII.

Referring to Fig. I of the drawings, 1 designates the base of the stand, which is constructed preferably, of metal.

Rigidly secured at the center of the base is rod 2, to provide a center of rotation.

Surrounding rod 2, and embedded in base 1 I have placed a roller bearing 3, whose rollers 3^a slightly protrude above the top surface of base 1.

The top of rod 2 is provided with a threaded shoulder 2^a.

The rod 2 is surrounded by a tube 4 to

which the circular plates 5 and 6 are fastened at its lower and upper ends respectively, and in this manner a spool is formed, which rests by its gravity on the rollers 3^a 60 and revolves on them easily. This spool is held in place by means of washer 7 and nut 8. Plates 5 and 6 are provided near their outer edges with a series of holes into which the hinge pins 9 are placed. These pins connect the ticket panels 10 by means of the hinge bars 11 and 12 to the plates 5 and 6.

The detail of a connection of an upper hinge bar 12 and pin 9 to plate 6 is shown in section by Fig. II. The length of the ticket 70 panels extends from the lower surface of plate 5 to the upper surface of plate 6, the hinge bars 11 and 12 are fastened to the lower and upper edges of the ticket panels, bars 11 move on the hinge pins 9 below plate 75 5 and bars 12 above plate 6.

The ticket panels 10 consist of a rectangular frame 13, preferably made of U-shaped cross section into which a plate 14, of wood or any other suitable material, is framed the 80 front of this plate 14 is covered by a sheet metal plate 15 to which the ticket holders 16 are fastened in a slanting position, forming parallel horizontal and vertical rows to hold series of tickets. The ticket holders 16 of 85 which a single one is shown in Fig. III are preferably stamped from a single sheet of metal by bending three of its edges 16^a, 16^b, 16^c, upward under right angles.

The formation of a ticket rack is illustrated by Fig. IV and Fig. V. The upper edge 16^d of the uppermost ticket holder is kept a short distance away from plate 15 by means of the distance piece 17. The lower edge 16^e of the same ticket holder is 95 fastened directly to plate 15 and in this manner the holder is brought into a slanted position. Another ticket holder 16 is laid upon this first one and fastened to it in such a manner, that the upturned vertical edges 100 16^a and 16^b form a plane with the corresponding edges of the first ticket holder but the edge 16^c of the upper holder is slantingly moved downward until it touches the plate 15 and is fastened thereto. By fastening in 105 this manner one ticket holder upon the edges of the upturned flanges of the one below a vertical row of the holders is formed and by placing and fastening the upturned edges 16^b of one row against the edges 16^c of another row the whole ticket rack is formed. It can be seen that by this arrangement each

ticket holder forms a box-like compartment with the next one above or below, which is completely closed on five sides and only open on its narrow upper side, for the introduction of the ticket 18. The lowest horizontal row of ticket holders is preferably covered with a plate 19. The fastening of the ticket holders to each other and to plates 15 and 19 may be done in any suitable manner, but 10 preferably by soldering or brazing.

While this revolving ticket rack holder serves to display the tickets in the racks and to find the desired ticket for any seat or performance easily, it will only accommodate 15 tickets for a relatively short period and I have provided the storage cabinet herein-after described to store safely a larger number of ticket racks, with or without the tickets until the proper time for their disposal arrives.

This storage cabinet is shown in Fig. VI it has the general appearance of a box or closet, with doors, at its front side, it is preferably made of sheet or plate steel and its 25 sides are joined by riveting, electric welding or in any other suitable manner. It consists of a rectangular bottom plate 20, to which are fastened the vertical sides 21, provided with ledges or feet 22 to give a solid bearing, the vertical back plate 23, the horizontal top plate 24 and above the latter the cover plate 25. The front side is formed by the double doors 26 and 27 connected to the vertical sides 21 by hinges 28. These doors are 30 provided with a lock 29 and cover the rectangular opening formed by the bottom plate 20, sides 21 and top plate 24. The front edge of the cover plate 25 does not extend forward to the plane of the door opening but is placed a short distance behind the latter. The vertical back 23 covers the rectangular opening formed by the rear edges of bottom plate 20, vertical sides 21 and the cover plate 25. The distance between the upper side of bottom plate 20 and the lower side of top plate 24 is approximately the same as the distance between the lower side of hinge bar 11 and the upper side of hinge bar 12 of a ticket panel 10 45 previously described. Plates 20 and 24 are each provided with a series of parallel slots 30 and 31 which reach from points near the door opening to points near the back 23. On both sides of each slot and parallel to 50 it, the guide angles 32 are arranged to guide the ticket panels into the cabinet. The panels are held in a manner similar to the one adopted for the revolving ticket stand, the hinge pins 9 are inserted through the 55 front end of a slot 31 in top plate 24 into the hole of an upper hinge bar 12 and similarly another hinge pin 9 through a lower hinge bar 11 into the front end of a slot 30 in bottom plate 20, as shown in Fig. VI. 60 The front end 32^b of the guide angles 32 is

so placed in relation to the front ends of slots 30 and 31 that the panels may be swiveled from side to side when the hinge pins are at the front ends of their slots as illustrated by Fig. VII. This figure shows also 70 that the front ends 32^b of the guide angles prevent the panel frame from slipping back into the guide way when the panel is slightly swung to one side. The cover plate 25 protects the upper hinge pins when the ticket 75 panels are in the cabinet, and the hinge pins at the rear ends of the slots as indicated by 9^a in Fig. VI.

When in use the tickets, which are generally printed for a long period in advance 80 of their use are assorted according to their date and location, one panel for instance may serve for one performance, and all filled panels are kept in the storage cabinet until the proper time arrives when the 85 panels holding tickets for the next performances are transferred to the revolving stand by removing the hinge pins from the slots in the ticket case and reinserting them through the holes in plates 5 and 6 of the 90 revolving stand. It will be observed that the ticket panels in the revolving stand are capable of two motions one around the hinge pins and a second one around the center rod 2. By the arrangement shown in Fig. 95 100 I every panel may be swung through a short arc only, around the hinge pin, when its rear edge will touch the plates 5 and 6 whereby the motion is transferred to these plates which then start to swing around the center rod 2. In this manner a quick inspection of all panels will be accomplished.

Having thus described my invention what I claim as new and desire to secure by Letters Patent is:

1. A ticket rack comprising a rectangular frame, surrounding a plate of sheet metal, backed by a plate of fibrous material, hinge bars on said frame, extending its top and bottom edges, provided with apertures for hinge pins, and ticket holders, formed by bending a rectangular plate at three sides at a right angle to the plate, fastened one upon the other in slanting position and forming rows of ticket compartments, held by said base, said ticket compartments having an entrance opening at their top and being closed on their other sides.

2. In a storage cabinet for tickets, a base section, three vertical sides, and a roof section, a door forming the front side of said cabinet, a series of alining elongated apertures in said base and roof sections extending from points near the door opening to points near the rear side of said cabinet, and ticket racks provided with alining projections at their upper and lower edges, apertures in said projections to accommodate hinge pins which slidably engage said alining apertures and rotate in said projections

3. In a storage cabinet for tickets, the combination with a casing having top and bottom plates provided with alining elongated apertures, of a plurality of ticket racks provided with projections at their upper and lower sides, slidably engaging said longitudinal apertures in the base and top plates of said casing and a protecting roof above said top plate covering the upper projections.
4. In a storage cabinet for ticket racks the combination with a casing provided with elongated apertures in its base and top plates, guide bars parallel to said apertures, and terminating slightly behind the front 15 end of said apertures, ticket racks sliding between said guide bars and provided with hinge bars, and hinge pins which slide in said apertures, at their upper and lower sides; said hinge bars engaging the front 20 edges of the guide bars when the hinge pins are at the extreme front end of the apertures and turned out of alinement with the apertures.

MAX A. SKALL.
